ABSTRACT: A centrifugal drum for treating web material by means of a liquid or gaseous substance, in which the marginal areas of a hollow drum with a perforated circumferential drum wall are gas or liquid tight sealed by inflatable hose means arranged within said hollow drum between the latter and a hollow shaft having said drum connected thereto for rotation therewith, said hoses also sealingly engaging said hollow shaft and being adjustable in the axial direction of said shaft.

CENTRIFUGAL WINDING DRUM FOR THE WET AND GAS TREATMENT OF TEXTILE WEB MATERIAL

The present invention relates to a centrifugal winding device with perforated drum upon which textile web material is wound and is treated by means of a liquid or gaseous treating medium introduced under pressure or under no pressure into the hollow drum. Thus, for instance, the wound up material is permeated with bleaching or dyeing liquor whereupon the web material is steamed by wet steam pressed therethrough or is fixed and finally is washed by means of hot or cold water pressed therethrough and is dried by means of introduced hot air. With centrifugal winders of the above mentioned type, considerable difficulties are encountered in sealing the marginal areas when goods are treated which are narrower than the range of the perforations. Previously, in order to meet situations like this, the free marginal areas were covered from the outside by textile or metal bandages of the required width. This method, however, has proved unsatisfactory because an absolute sealing could not be realized and because, above all, during a steam treatment the work shop was very quickly filled with steam clouds. Furthermore, in case the material broke or tore, life endangering accidents occurred which frequently resulted in burns and other injuries.

According to other suggestions, cover discs were arranged inside the drum which cover discs, however, likewise were not sealtight.

In an effort to overcome the above mentioned drawbacks, it has been suggested so to subdivide the interior of the drum into chambers that depending on the respective requirements, one or more marginal chambers were selectively turned off or made ineffective. Such an arrangement, however, is very expensive and the construction is rather heavy which is particularly disadvantageous in view of the high centrifugal forces. The device was furthermore adjustable only in large steps which is a further important drawback.

It is, therefore, an object of the present invention to provide a device of the above mentioned general type, which will overcome the drawbacks of heretofore known devices of the type involved.

This object and other objects and advantages of the invention will appear more clearly from the following specification in connection with the accompanying drawing, in which:

FIG. 1 shows in axial section a portion of a centrifugal drum according to the present invention, said section being taken along the line I—I of FIG. 2.

FIG. 2 is an end view of FIG. 1 as seen in the direction of the arrow A.

The objects according to the present invention have been realized by sealing the open ends of a centrifugal drum fixedly arranged on a hollow shaft by longitudinally displaceable pneumatic hoses which are arranged between the inner drum surface and the hollow shaft.

Referring now more specifically to the drawing, the centrifugal drum 3 provided with perforations or bores 3a and having wound thereon the goods 1 to be treated is fixedly arranged on a hollow winding shaft 5 by means of two spacer discs 4 arranged at a greater distance from the ends of the drum. The winding shaft 5 is advantageously designed light and comprises a pipe 5 provided with a plurality of bores 6. Pressed into both ends of the pipe 5 are solid bearing studs 7 with bores 8. The bore 8 serves for feeding the treating medium which through the bores 6 passes into the chamber between the drum 3 and shaft 5 and through bores 6a in the spacer discs to the perforations and from there into the wound up goods.

The adjustable pneumatic sealing device for closing the drum perforations which are exposed at the marginal area of the drum comprises, in conformity with the specific example shown, two coaxially arranged hoses 9, 10 of which the hose 9 having the larger diameter engages the drum wall 3 whereas the hose 10 with the smaller diameter engages the shaft 5.

Both hoses are journaled on annular surfaces 11 and 12 which are fixedly arranged on a disc 13 which is perpendicular to the axis of the drum and is axially displaceable. Between the two annular surfaces 11 and 12 there are welded-in three nuts 14 offset with regard to each other by 120° or four nuts 14 offset with regard to each other by 90°. These nuts 14 are threadedly engaged by adjusting spindles 15 which are adjustable from the outside by means of a squarehead wrench. The length of the adjusting spindles 15 is so selected that the hoses may be adjusted up to the maximum occurring adjusting stroke. In order to prevent the steam or liquor from escaping outwardly through the nuts, the disc 13 has welded thereon bushings 16 which are directed toward the interior of the drum and which can move in bores 17 of the spacer discs 4. The annular chambers for receiving the hoses 9 and 10 are closed toward the outside by discs 18 which are screwed against the discs 13 by means of threaded bolts 19. In this way, the annular chambers are confined from all sides whereby, when pressure is conveyed into the hoses, the latter will in a pressuretight manner rest against the winding-up drum and the shaft 5.

The displacement of the two hose systems from the drum ends in the direction toward the drum center for purposes of confining narrower webs of goods, is effected by the above mentioned threaded spindles 15 which rest in the drum end discs 20 by means of collars.

The drum end discs 20 additionally center the drum ends and are pressed against the drum ends by means of nut rings 21 screwed onto the shaft stud. The detachability of the drum end discs 20 and the annular chamber discs 18 is necessary in order to be able whenever desired to exchange the pressure hoses 9 and 10.

In order to be able to post-tighten the threaded bolts 19, the drum end discs 20 are provided with correspondingly large bores 22. For assuring a uniform movement and a precisely axis-parallel displacement of the hose system, all adjusting spindles 15 are outside said end discs provided with detachable sprocket wheels 23 and are connected to each other by a common driving chain 24.

The cross section of the hoses is so selected that on one hand a sufficient seal of the marginal bores will be assured while on the other hand the building width of the hose system is as narrow as possible. The hoses 9, 10 are, of course, provided with valves 25, 26 respectively for inflating and deflating same.

An additional advantage of the invention consists in that the adjustment for the various widths of the goods may, for all practical purposes, be effected in a stepless manner.

It is, of course, to be understood that the present invention is, by no means, limited to the particular construction referred to above but also comprises any modifications within the scope of the appended claims.

What we claim is:

1. A device for winding up web material, especially textile web material, for subjecting the same to treatment by a fluid substance, which includes: shaft means, drum means adapted on the outside thereof to receive the web material to be treated, said drum means having a perforated circumferential wall connected to and surrounding said shaft means so as to define therewith an annular chamber adapted to receive a fluid substance for treating web material received on said drum means, and pneumatic hose means arranged annularly within said annular chamber and inflatable so as to sealingly engage said shaft means and said perforated wall of said drum means, said hose means being adjustable in the axial direction of said drum means.

2. A device according to claim 1, in which said shaft means is hollow and has a perforated circumferential wall, said hollow shaft means including means for conveying a treating fluid substance to the interior of said shaft means and through the perforated circumferential wall thereof into said annular chamber.

3. A device according to claim 1, in which said drum means is provided with two pairs of hose means arranged at opposite

end portions of said drum means, and in which each of said hose means includes an annular inner hose having its inner circumferential surface in sealing engagement with said shaft means, and an annular outer hose having its outer circumferential surface in sealing engagement with said drum means.

4. A device according to claim 3, which includes annular supporting means surrounding said shaft means in radially spaced relationship thereto and forming outer and inner compartments respectively having said outer and inner hoses located therein, and adjusting means operatively connected to said supporting means for selectively adjusting said supporting means and thereby said hoses in the axial direction of said drum means.

5. A device according to claim 4, which includes supporting means arranged at each end portion of said drum means, each of said supporting means comprising two coaxially arranged annular members substantially coaxial with said shaft means

and also comprising two annular disc means spaced from each other in the axial direction of said drum means and connected to said annular members, and in which said adjusting means includes nut means connected to and interposed between said two coaxially arranged annular members and also includes spindle means extending in the axial direction of said drum means and threadedly engaging said nut means.

6. A device according to claim 5, which includes end disc means detachably connected to the end portions of said drum means and axially nondisplaceably but rotatably supporting said spindle means.

7. A device according to claim 5, in which the two annular disc means pertaining to one and the same supporting means are detachably connected to each other for permitting ready access to the respective hoses therebetween.
